CLAIM

The ornamental design for an input/output terminal for a cash register or similar article, as shown and described.

DESCRIPTION

FIG. 1 is a top, front, left side perspective view of an input/output terminal for a cash register or similar article showing my new design;

FIG. 2 is a right side elevational view thereof on an enlarged scale;

FIG. 3 is a left side elevational view thereof on an enlarged scale;

FIG. 4 is a rear elevational view thereof on an enlarged scale;

FIG. 5 is a front elevational view thereof on an enlarged scale;

FIG. 6 is a top plan view thereof on an enlarged scale;

FIG. 7 is a bottom plan view thereof on an enlarged scale.

FIG. 1

FIG. 2

FIG. 3

FIG. 4

FIG. 5

FIG. 6

FIG. 7
